SHEET FEEDING APPARATUS

Albert Broadmeyer, Harrisburg, Pa., assignor to
W. O. Hickok Manufacturing Company, Harrisburg, Pa., a corporation of Pennsylvania

Application November 21, 1931
Serial No. 576,573

9 Claims. (Cl. 271—62)

In sheet feeding mechanisms and particularly that type in which the sheets are presented as in a pile so that the topmost are successively removed, the range of the sizes of sheets that can be successfully fed has heretofore so far as I am aware, been considerably limited by reason of the character of the "feeler" and its mounting, this "feeler" as is well known determining the elevation of the pile of sheets. The mounting of the feeler has been such with respect to the feeding device that the part which rests upon the paper cannot be brought closely to the feeding device and consequently sheets of small area and on which the feeler must rest cannot be fed because the feeler then is so close to its mounting that it has not sufficient leverage to easily move under the influence of the underlying pile.

One of the objects of the present invention is to provide an arrangement of parts which will permit the feeler to be brought very close to the feeding device and still be sufficiently distant from its mounting to allow its easy movement and consequently control the operation of the pile feeding mechanism.

Another object is to simplify the control mechanism and make it very delicately responsive to the action of the feeler.

In the accompanying drawings:

Figure 1 is a side elevation of a well-known type of sheet feeder in which the improvements are embodied.

Figure 2 is a top plan view of a portion of the same.

Figure 3 is an enlarged plan view with portions removed to better illustrate the novel arrangement and parts.

Figure 4 is a side elevation on an enlarged scale with portions removed in order to show the table elevating mechanism and the control means therefor.

Figure 5 is a detail view of the pawl carrier.

Figure 6 is a detail view of the bracket support for the detent.

Figure 7 is a detail view of the detent.

Figure 8 is a detail horizontal sectional view on the line 8—8 of Figure 1.

Figure 9 is a cross sectional view on the line 9—9 of Figure 8.

Figure 10 is a detail sectional view on the line 10—10 of Figure 3.

Figure 11 is a detail view in section of the bracket and mounting for the actuating arm of the detent.

Figure 12 is a detail sectional view of the journal bearing for the feeder rock shaft.

Figure 13 is a sectional view of the mounting for the pawl.

Figures 14 and 15 are views in elevation and schematic in their character showing how different sized sheets may be placed and the mechanism properly related thereto.

In the embodiment disclosed, a suitable frame 16 is employed, which includes standards 17. A shaft 18 suitably driven, extends across the frame and is provided with a feeding device 19. This feeding device is in the form of a suction roller of well-known type, which is connected by a conduit 20 to a vacuum-creating pump (not shown). In the conduit 20 is the usual valve 21 which controls the creation of vacuum in the roller 19 and is automatically operated. These parts, it is believed, are so well known that they need no further exposition to those skilled in the art.

The sheets to be fed by the feeding device 19 are placed in a pile 22 on a table 23 that is mounted, as indicated at 24, to vertically slide on the standards 17. The table is supported by sprocket chains 25, that pass around sprocket wheels 26 on stub shafts 27 that are journaled on the top of the frame 16. These shafts have worm wheels 28 meshing with worms indicated at 29 (see Figure 4) that are carried by a transverse horizontal shaft 30.

The shaft 30 is provided at one side of the machine with a ratchet wheel 31 and the teeth of this ratchet wheel are operated on by a pawl 32 carried by the upper end of an oscillatory pawl carrier 33 journaled on the shaft 30 alongside the ratchet wheel 31. The pawl carrier is caused to oscillate, its movement in one direction being by gravity and its movement in the other direction is secured by a link 34 having a crank mounting 35 on a crank wheel 36 that is fixed to the end of the shaft 18. The link 34 is provided with a slot 37 in which is engaged a pin 38 mounted in the lower end of the pawl carrier 33. It will be obvious that as the shaft 18 rotates the slotted end of the link 34 will be given a reciprocating movement, and when moving to the left (Figures 1 and 4), the lower end of the pawl carrier by gravity moves in the same direction, causing the pawl 32 to ride over one or more teeth of the ratchet wheel 31. When the link 34 moves to the right the end wall of the slot engaging the pin 38 will swing the pawl carrier in the opposite direction, and the pawl engaging behind one of the teeth of the ratchet wheel will cause a partial rotation of the shaft 30. This will effect a movement of the stub shafts 27, and drawing upon the chains 25, will elevate the table carrying the pile of sheets.

to be fed. This mechanism as thus far described is well known.

To control the elevation of the table as the topmost sheets are successively fed from the pile by the suction roller 19, the following mechanism is employed. A rock shaft 39 is journaled transversely in the frame, and it will be noted is behind the shaft 18, which carries the suction roller 19, or in other words, is at the side of the feeder 10 toward which the sheets are delivered by the roller 19. Mounted on an intermediate portion of the rock shaft 39 is a split collar 40, the jaws 41 being connected by a screw 42 having a hand bar 43, by means of which it may be readily turned to 15 loosen or tighten the jaws upon the shaft 39. This collar includes an extension 44 having a socket 45 in which is engaged a feeler arm 46 held by a set screw 47. The feeler arm, it will be noted by reference to Figure 3, extends across the 20 shaft 18 above the same and overlies the pile supporting table 23. Slidably mounted on this arm 46 is a bracket 48 which can be secured in any desired position by a set screw 49. This bracket has secured thereto a depending finger 50 carrying a knife blade 51 that constitutes a bearing element on the top of the pile 22.

On the front projecting end of the shaft 39 is fixed a bracket 52 having a depending lug 53 in which is engaged the offset end 54 of an arm 55. 30 On this arm is adjustably mounted a counterweight 56 that is held in fixed position by a set screw 57.

The bracket 52 at its upper end is in the form of a yoke having arms 58 and 59. An actuating arm 60, journaled in the shaft 39, is provided with an upstanding finger 61 that extends between the yoke arms 58 and 59. The finger 61 is pressed against on one side by a plunger 62 slidably mounted in the arm 58 and yieldingly urged against said finger 61 by a spring 63 in a chamber 64 formed in an extension of said arm 58. The opposite side of the finger 61 is abutted against by the end of an adjusting screw 65 threaded through the arm 59.

45 The arm 60, as shown in Figures 3 and 4 extends forwardly alongside the frame 16, and consequently if the feeler arm 46 is raised or lowered, the arm 60 will be correspondingly raised or lowered. The free end of the arm has a pair of spaced outstanding pins 66 that straddle the rearwardly extending finger 67 fixed to an upstanding detent 68 pivotally mounted at 69. The detent pivot 69 is carried by a bracket 69a. The detent is counterweighted as shown at 70. The 50 upper end of this detent is movable to and from a position underneath a stop tooth 71 that is fixed upon the rear side of the pawl carrier substantially midway of its length. As shown in detail in Figure 5, this tooth 71 preferably has a shank 72 fitted in a socket in the pawl carrier and held by a set screw 73.

With this structure it will be evident that when the pile 22 of sheets is at the proper elevation so that the topmost sheet will be fed rearwardly by the suction roller 19, the knife blade 51, resting on the sheets, will hold the feeler arm 46 and arm 60 at an elevation to cause the detent 68 to be beneath the tooth 71. The pawl carrier 65 therefore is held idle. That is to say, as the shaft 18 rotates and the link 34 is caused to move back and forth, the slot 37 of said link will permit the free movement of the link, but the pawl carrier 70 is held by the detent so that it cannot move by 75 gravity a distance sufficient to cause the pawl

to move rearwardly over a tooth of the ratchet wheel 31. Therefore the table-elevating means is idle. As the sheets are successively removed by the suction roller 19, the knife blade 51 will gradually move downward and a corresponding movement of the arm 60 will take place inasmuch as the abutment screw 65 will press upon the finger 61 of said arm 60. When the movement has been sufficient the detent 68 will be moved rearwardly out of the path of the tooth 71. Thereupon the pawl carrier will be free to gravitate and the pawl being thrown into action, will cause the operation of the ratchet wheel 31 and the table will be elevated until the feeler has again been raised to a point sufficient to cause the arm 60 to again move the detent 68 under the tooth 71.

In order to manually raise or lower the table, the shaft 30 has fixed thereto a collar 74 (see Fig. 8), and a hand wheel 75, rotatably and slidably mounted on the shaft on the outer side of the pawl carrier, is provided with a rearwardly projecting pin 76 that is adapted to engage in any of a series of sockets 77 in the collar 74 as shown in Figure 9. When so engaged, by turning the wheel 75, the shaft 30 can be manually turned and if the pawl 32 is disengaged from the ratchet wheel, the shaft can be rotated in either direction to raise or lower the table. When the pin 76 is disengaged from the collar 74, obviously the wheel will remain idle.

Attention has already been called to the fact that the rock shaft 39, which carries the feeler arm 46, is at the rear side of the suction roller, whereas the feeler blade 51 and its mounting 110 is on the opposite side of the suction roller. The arm 46 is long enough to permit the blade 51 to be placed at the rear margin of the sheets of a pile that will fully occupy the table 23 as shown in Figures 1 and 14. But the apparatus is practical for use on very small sheets or cards, as will be clear by reference to Figure 15. That is to say, when a pile of small sheets or cards is placed in position to be operated on by the suction roller, the knife blade or feeler blade 51 can be brought up very close to the suction roller or its axis of rotation and will still be far enough from the rock shaft 39 to afford the necessary leverage to be elevated by the pile when the latter is moved upwardly and to drop when the pile is depleted by the feeding device. Moreover the extended length of the arm 46 when in such a position and which would obviously have considerable weight, is overcome merely by the adjustment of the counterweight 56 on its arm 55. The mechanism therefore is capable of successful use on sheets having a wide variety in size and shape.

The mechanism that directly controls the operation of the detent 68 is also advantageous. In the first place it is extremely simple and compact and allows the necessary "give" to the parts if they do not immediately come into coacting relation. For example should the tooth 71 be depressed when the detent 68 is moved towards its active position and the upper end of the detent should strike the end of the tooth 71, the plunger 62 which acts on the finger 61 to cause the elevation of the arm 60, will retreat and allow the parts their necessary movement notwithstanding the fact that the arm 60 is momentarily held. As soon as the tooth 71 rises to clear the upper end of the detent, then the spring 63 will react and operating on the plunger 62 will press against

the finger 61, elevating the arm 60, and causing the detent to pass beneath the tooth 71.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What I claim is:

1. In a sheet feeder, the combination with a vertically movable pile supporting table and mechanism for effecting its vertical movement including a ratchet wheel, a pawl that actuates the ratchet wheel, a pawl carrier, and means for actuating the pawl carrier, of mechanism for governing the operation of the pawl carrier including a detent, a rock shaft, a feeler arm on the rock shaft, a second arm having a yielding mounting on the rock shaft and normally swinging upon its rotation, and a connection between the second arm and the detent to cause the former to move the latter.

2. In a sheet feeder, the combination with a vertically movable pile supporting table and mechanism for effecting its vertical movement including a ratchet wheel, a pawl that actuates the ratchet wheel, a pawl carrier and means for actuating the pawl carrier, of mechanism for governing the operation of the pawl carrier including a detent, a rock shaft, a feeler arm on the rock shaft, a bracket fixed to the rock shaft, and a detent actuating arm having a swinging mounting on the rock shaft that is limited by the bracket.

3. In a sheet feeder, the combination with a vertically movable pile supporting table and mechanism for effecting its vertical movement including a ratchet wheel, a pawl that actuates the ratchet wheel, a pawl carrier and means for actuating the pawl carrier, of mechanism for governing the operation of the pawl carrier including a detent, a rock shaft, a feeler arm on the rock shaft, a bracket fixed to the rock shaft, a detent actuating arm having a swinging mounting on the rock shaft, and means engaging the arm and bracket for permitting a varied limited movement of the rock shaft with respect to the arm.

4. In a sheet feeder, the combination with a vertically movable pile supporting table and mechanism for effecting its vertical movement including a ratchet wheel, a pawl that actuates the ratchet wheel, a pawl carrier, and means for actuating the pawl carrier, of mechanism for governing the operation of the pawl carrier including a detent, a rock shaft, a feeler arm on the rock shaft, a bracket fixed to the rock shaft, a detent actuating arm having a swinging mounting on the rock shaft, an adjustable abutment for the arm carried by the bracket, and a yielding abutment for the arm carried by the bracket and opposed to the adjustable abutment.

5. In a sheet feeder, the combination with a sheet feeding device and a shaft carrying the same, of means for presenting sheets to be fed to the feeding device, and mechanism for controlling the operation of the sheet presenting means including an arm that extends transversely of and above the shaft and on opposite sides of the feeding device, a mounting for the arm at the side of the feeding device toward which the sheets are delivered by said device, and a bearing device

mounted for adjustment along the arm toward and from the feeding device and located at the opposite side of the feeding device to the mounting, said bearing device being adapted to rest on the sheets at a point remote from the feeder and mounting and adjustable toward and from the shaft and feeding device carried thereby to adapt it to different sizes of sheets.

6. In a sheet feeder, the combination with a sheet feeding device, of means for presenting sheets to be fed to the feeding device, and mechanism for controlling the operation of the sheet presenting means including an arm that extends on opposite sides of the feeding device, a mounting for the arm at the side of the feeding device toward which the sheets are delivered by said device, a bearing device mounted for adjustment along the arm toward and from the feeding device and located at the opposite side of the feeding device to the mounting, said bearing device being adapted to rest on the sheets at a point remote from the feeding device and mounting and adjustable to different sizes of sheets, and an adjustable counterbalance for the arm to compensate for the position of the bearing device in its different positions thereon.

7. In a sheet feeder, the combination with a sheet feeding device, of a rock shaft located at the side of the feeding device toward which the sheets are fed by said device, a swinging arm mounted on the rock shaft and extending to the opposite side of the feeding device, a bearing device adjustable along the arm toward and from the feeding device and being located on said opposite side thereof to the rock shaft, said bearing device being adapted to rest on the sheets at a remote distance from the rock shaft, an oppositely extending arm connected to the rock shaft, a counterbalance adjustable along the arm to compensate for the bearing device in its different positions, means for presenting the sheets to the feeding device, and mechanism actuated by the rock shaft for controlling the operation of said sheet presenting means.

8. In a sheet feeder, the combination with a shaft and a sheet feeding device mounted thereon, of a rock shaft located at the side of the shaft and feeding device toward which the sheets are fed by said device, a swinging arm mounted on the rock shaft and extending over the shaft to the opposite side of the feeding device, a bearing device adjustable along the arm toward and from the feeding device and being located on said opposite side thereof to the rock shaft, said bearing device being adapted to rest on the sheets at a remote distance from the rock shaft, means for presenting sheets to the feeder, mechanism for actuating the sheet presenting means including a ratchet wheel, a pawl acting on the ratchet wheel, means for moving the pawl, a detent for holding the pawl, a second arm mounted on the rock shaft and extending forwardly to the opposite side of the feeding device therefrom, and means connected to the free end portion of the second arm in advance of the feeding device for actuating the detent.

9. In a sheet feeder, the combination with a sheet feeding device and an adjustable table on which the sheets are placed to be fed by said device, a rock shaft journaled in rear of the sheet feeding device, a forwardly extending feeler arm mounted on the rock shaft and extending to the opposite side of the feeding device and toward the front of the table, a bearing device adjustably mounted on the arm and movable to different

positions at different distances from the feeding device, a rearwardly extending arm connected to the rock shaft, a counterweight adjustably mounted on the rearwardly extending arm, a second forwardly extending arm mounted on the rock shaft and projecting beyond the opposite side of the feeding device, and having an up and down motion at its front end, ratchet mechanism for

operating the table, means for controlling the operation of the ratchet mechanism including a detent operating finger operated by the forwardly extending arm and having an up and down movement, and a detent actuated by said detent 80 operating finger.
